The ornamental design for a garlic press, as shown and described.

DESCRIPTION

FIG. 1 is a side elevational view of a garlic press showing my new design in an open position;

FIG. 2 is a top plan view thereof;

FIG. 3 is a side elevational view thereof in a closed position;

FIG. 4 is a bottom plan view thereof with cover "A" removed;

FIG. 5 is a bottom plan view thereof;

FIG. 6 is an exploded front elevational view thereof, the opposite side being a mirror image; and,

FIG. 7 is a perspective view thereof in an open position.
